STEAM IRON

Joseph C. Wayne, Chicago, Ill., assignor, by mesne assignments, to Whirlpool Corporation, a corporation of Delaware.

Application September 28, 1956, Serial No. 612,765

2 Claims. (Cl. 38—77)

This invention relates to a steam iron.

In a common type of steam iron, a water reservoir is positioned within the body of the iron, and valve means are provided to feed water a small amount at a time from this reservoir to a steam producing chamber in the sole plate of the iron adjacent to the heating element. In a common type of iron, this reservoir is provided with an upwardly extending fill tube which can be located in a part of the front handle support. This fill tube is provided with an opening so that water can be introduced through the filling opening and through the fill tube into the reservoir when additional supplies of water are required.

One of the chief disadvantages of an iron of this type is that often water is expelled up through the fill tube and out the filling opening either when the iron is moved back and forth violently during the ironing operation or when the iron is permitted to stand with the switch to the heating element in the "on" position so that as the water in the reservoir gets hotter and hotter the vapor pressure on this water becomes sufficiently great to eject slugs of water as previously described.

The present invention successfully solves these difficulties by providing barriers and baffles that permit the flow of water into the reservoir, but restrict the flow of water from the reservoir outwardly through the fill tube and its opening.

The invention will be described as related to the embodiment shown in the accompanying drawings. Of the drawings:

Figure 1 is a partially broken-away side elevational view partially in section of the steam iron embodying this invention;

Figure 2 is a sectional elevational view of the water reservoir taken substantially along line 2—2 of Figure 1;

Figure 3 is a sectional elevational view taken substantially along line 3—3 of Figure 2; and

Figure 4 is a sectional elevational view taken substantially along line 4—4 of Figure 1.

The iron shown in the accompanying drawings, except for the construction features forming the subject of this invention, is similar to the iron shown in P. J. More et al. U.S. Patent 2,744,343, dated May 8, 1956. Thus, the iron comprises a sole plate 10 having a tubular heating element 11 embedded therein and containing a steam generator including a steam generating chamber 12 located within the sole plate. The steam generating portion and steam distributing portion of the iron are of the usual type in which water is converted to steam in one portion of the sole plate and ejected through passages in the bottom surface of the sole plate onto the material being ironed. Such steam generator and conduit systems are common to steam irons of this type and are well known to those skilled in the art.

Positioned on the top of the sole plate 10 is a closure plate 13, which operates as a closure for the steam generating chamber 12. Located above this plate 13 is a water reservoir 14 that is enclosed within a sheet metal

hood 15. On top of this hood is positioned a handle 16 having a hollow front post 16a and a rear post 16b. The bottom portion 16c of the handle contains a control knob 17 for regulating the temperature of the iron. The bottom portion 16c is connected by a plurality of screws 18 to the top of the hood 15.

Attached to the front upper portion of the reservoir 14 and extending generally upwardly into the hollow front post 16a and exposed at the front thereof is an apparatus including a fill tube 19 provided with a bottom flange 19a rolled over to grasp tightly the marginal edge of an opening in the front upper portion of the reservoir so that the flange 19a describes a filling opening for a reservoir. The fill tube is provided with a front wall 19b exposed at the front of the iron and containing a generally circular water inlet opening 19c. This water inlet opening leads into the hollow interior 19d of the fill tube 19. In the embodiment shown, the portion of the fill tube immediately behind the inlet 19c is flared on both sides as indicated at 19e on opposite sides of the inlet 19c and then curved inwardly to join the interior 19d, which has a cross-sectional shape with substantially parallel sides and an arcuate rear side as shown in Figure 4. The interior of the fill tube beneath the portion 19e has a front surface 19g curved on a relatively large radius, with this front surface being immediately beneath the inlet 19c. The sides of the surface 19g extend beyond the sides of the opening 19d so as to provide laterally projecting side groove portions 19h, as indicated in Figure 4. These side groove portions 19h are substantially parallel to each other and sloped downwardly and rearwardly, as indicated in Figure 1.

In order to control the flow of water between the reservoir 14 and the steam chamber 12, there is provided a valve 20 having generally the structure shown and described in the above-mentioned patent, 2,744,343. The valve 20 is mounted on an inverted essentially dish-shaped metal stamping 21, which in turn is mounted on the closure plate 13 so as to extend across an opening 13a therein. The valve 20, which is mounted on the stamping 21, has its bottom extending through this opening 13a. The edge of the stamping 21, which is essentially planar, is held on the plate by a rolled edge part 13b.

The operating stem of the valve 20 is in the form of a rotatable rod 22 extending upwardly through the reservoir 14 and through the fill tube 19 and through the upper end thereof. In order to hold the rod 22 for rotational longitudinal movement in controlling the flow of water through the valve 20 into the steam chamber, the upper end of the fill tube 19 is provided with an internally threaded opening rotatably supporting a threaded member 23 to which the rod 22 is secured. The upper end of the rod 22 beyond the member 23 is serrated longitudinally and slidably engages a similar serrated opening 24a extending through a rotatable disc 24 housed within a slot 16d in the upper front part of the handle 16. The disc 24 extends beyond the slot on the front and sides so as to be readily grasped by the hand for rotation of the disc and adjusting the rate of flow of water through the valve 20 in the manner described in the above-mentioned patent.

When it is desired to introduce water into the reservoir 14, it is only necessary in an iron of this type to elevate the front end so that the water inlet 19c extends generally upwardly. Water can then be poured into the inlet 19c and it will flow through the interior of the fill tube and through the inlet opening of the reservoir into the reservoir itself.

In order to inhibit the accidental ejection of water from the reservoir up through the fill tube and out the inlet 19c onto the material being ironed while the iron is in use or while it is at rest with electricity flowing

through the heating element 11, a transverse barrier plate 25 is provided extending across the hollow interior of the fill tube beneath the inlet 19c. As is shown most clearly in Figure 4, this barrier 25 has its front end 25a contacting the interior surface 19g, a narrow rear end 25b contacting the rear curved surface, and laterally extending side portions 25c extending into the side grooves 19h of the fill tube 19.

In order to provide passages for the flow of water downwardly from the reservoir to the inlet 19c, the rear lateral sides of the plate are shaped similarly, but spaced from the corresponding side portions of the hollow interior of the fill tube 19. Thus, as shown in Figure 4, the rear edges of the barrier plate 25 from the rear edges of the side portions 25c are spaced from the sides of the fill tube opening 19d and grooved portions 19h except for the small rear end 25b of the barrier plate. In addition, an oval opening 25d is provided in the barrier plate through which the valve operating rod 22 extends. With this arrangement, the opening 25d and the resulting side openings, indicated at 26, provide ample space for water to flow past the barrier plate into the reservoir when the reservoir is being provided with water. However, the barrier plate serves as an impediment to restrict the flow of water in the opposite direction. This impediment or barrier is particularly effective because of the provision of the solid plate portion 25a at the front of the plate so that no opening is provided immediately beneath the fill tube inlet 19c.

In order to provide an additional hindrance to the accidental ejection of water from the reservoir to the fill tube 19, there is provided in the reservoir a baffle having a portion in the area adjacent to the filling opening sloped to direct flowing water in the reservoir toward the sides of the reservoir rather than toward the opening formed by the flange 19a. In the embodiment shown, this baffle structure 26 includes a first baffle portion 27 extending transversely of the reservoir rearwardly of the opening formed by the flange 19a and having forwardly curved ends 27a. The baffle structure also includes second and third baffle portions 28 and 29 extending forwardly of the first baffle portion 27 substantially parallel to each other and on opposite sides of the central part of the opening 19a. The extreme forward ends of the essentially vertical baffles 28 and 29 are diverging, as indicated at 28a and 29a. The first and second baffle portions 28 and 29 are joined at the rearward ends by transverse portion 30 to form a generally U-shaped structure. The transverse portion 30 is located forwardly of and substantially parallel to the central part of the first baffle portion 27 and has its bottom joined to the

bottom of this first baffle by means of a web 31 that rests on the bottom of the reservoir 14. As can be seen in Figure 1, the diverging ends 28a and 29a are located just forwardly of the center of the bottom of the fill tube 19.

The top and bottom edges of the first baffle portion 27 are adjacent to the top and bottom of the reservoir 14. These top and bottom edges of the baffle portion 27 are provided with slots 27b and 27c. These slots or openings permit the passage of water past the baffle but break up sudden surges of water such as occur when the iron is propelled over the surface being ironed.

The bottom edges of the second and third baffle portions 28 and 29 are spaced from the bottom of the reservoir 14. The transverse portion 30 of the baffle structure is provided with a slot or cut-away portion 30a also to permit the restricted passage of water past the baffle structure.

Having described my invention as related to the embodiment shown in the accompanying drawings, it is my intention that the invention be not limited to any of the details of description, unless otherwise specified, but rather be construed broadly within its spirit and scope as set out in the accompanying claims.

25 I claim:

1. A steam iron, comprising: a water reservoir having a water inlet therein; an open fill tube extending upwardly from said inlet having a front wall and side walls and having a permanently open fill opening in the front wall of the fill tube; and a transverse barrier in the fill tube having a front edge engaging the fill tube front wall directly beneath the fill opening and side edges spaced from the side walls of the fill tube so as to provide a passageway from the fill opening to the reservoir.
- 30 2. The steam iron of claim 1 wherein the interior of the fill tube in the region of the barrier directly beneath the fill opening has a transversely widened portion and the barrier is similarly transversely widened to be substantially co-extensive with said widened portion of the fill tube.
